(57) **CLAIM**

We claim the ornamental design for a patella resection guide, as shown and described.

DESCRIPTION

FIG. 1 is a perspective view of a design of a patella resection guide;

FIG. 2 is a first side elevation view of the patella resection guide of FIG. 1 shown removed from its environment in order to show aspects of the design that are not apparent in the perspective view;

FIG. 3 is a second side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The features shown in broken lines depict environmental subject matter only and form no part of the claimed design.
